UNITED STATES PATENT OFFICE

160,509

GAME BOARD

Irving Lomsky, Cleveland, Ohio

Application April 14, 1949, Serial No. 1,982

Term of patent 3½ years

(Cl. D34—5)

To all whom it may concern:

Be it known that I, Irving Lomsky, a citizen of the United States, residing in the city of Cleveland, county of Cuyahoga, and State of Ohio, have invented a new, original, and ornamental Design for a Game Board, of which the following is a specification, reference being had to the accompanying drawing, forming a part hereof.

I claim:

The ornamental design for a game board, substantially as shown.

IRVING LOMSKY.
